UNITED STATES PATENT OFFICE.

JAMES MORRISON, OF CINCINNATI, OHIO, ASSIGNOR TO THE HIGHLAND BODY MFG. COMPANY, OF ELMWOOD PLACE, OHIO, A CORPORATION OF OHIO.

DESIGN FOR AN AUTOMOBILE-BODY.

46,573.

Specification for Design.

Patented Oct. 20, 1914.

Application filed July 28, 1914. Serial No. 853,715. Term of patent 3½ years.

To all whom it may concern:

Be it known that I, JAMES MORRISON, a citizen of the United States, residing at Cincinnati, in the county of Hamilton and State of Ohio, have invented a new, original, and ornamental Design for an Automobile-Body, of which the following is a specification, reference being had to the accompanying drawing, forming part thereof.

The figure is a perspective view of an automobile body showing my new design.

I claim:

The ornamental design for an automobile body as shown.

JAMES MORRISON.
